DESIGN FOR A WALL VASE

John C. Meeks, Woodland, Calif.

Application February 29, 1944, Serial No. 112,750

Term of patent 3½ years

(Cl. D29—28)

To all whom it may concern:

Be it known that I, John C. Meeks, a citizen of the United States and a resident of the city of Woodland, county of Yolo, State of California, have invented a new, original, and ornamental Design for a Wall Vase, of which the following is a specification, reference being had to the accompanying drawing, forming a part hereof.

I claim:

The ornamental design for a wall vase, as shown.

JOHN C. MEEKS.
